UNITED STATES PATENT OFFICE.

LEE S. CHADWICK, OF SHAKER HEIGHTS VILLAGE, OHIO, ASSIGNOR TO PERFECTION STOVE COMPANY, BY CHANGE OF NAME, OF CLEVELAND, OHIO, A CORPORATION OF OHIO.

DESIGN FOR A STOVE.

Application filed August 23, 1922. Serial No. 3,527. Term of patent 14 years.

To all whom it may concern:

Be it known that I, LEE S. CHADWICK, a citizen of the United States, residing at Shaker Heights Village, in the county of Cuyahoga and State of Ohio, have invented a new, original, and ornamental Design for Stoves, of which the following is a specification, reference being had to the accompanying drawing, forming part hereof, wherein the figure is a perspective view of a stove, exhibiting my new design.

I claim:

The ornamental design for a stove as shown.

LEE S. CHADWICK.
